ABSTRACT OF THE DISCLOSURE

The invention is concerned with a self-advancing mine roof support comprising two units connected together by pressure-fluid actuated means operative to advance the units in turn. An elevated forwardly projecting member is provided on the front of the support and in conjunction with corresponding members of other supports, positioned along the mineral face, carries an elevated track for a mineral mining machine. The front of the support also has mounted on it a conveyor means for collecting and carrying away the mined mineral. The forwardly projecting member which carries the track for the mining machine may be supported by a pressure-fluid ram means. The conveyor means may comprise a section of trough adapted, in conjunction with similar sections of trough of other supports, to receive an endless chain carrying paddles, scrapers or the like which runs along the trough formed by said sections.

This invention is for improvements in or relating to methods of mineral (e.g. coal) mining and equipment for use in such methods.

A method of longwall mining now well known makes use of self-advancing roof supports which are advanced in turn or in groups towards the newly exposed mineral face following the advance of the face conveyor. In one arrangement the supports comprise two units one behind the other and hydraulic ram means which, when operated in one direction, using the rear unit as an abutment, pushes the front unit towards the newly exposed mineral face and when operated in the other direction, using the front unit as an anchorage, advances the rear unit, the units having temporarily, in turn, been relieved of roof pressure. Such methods have not heretofore been applicable to short wall methods of mining (e.g. the working of the stable) and one object of the present invention is to apply such methods to short wall mining.

According to the present invention there is provided a method of mining in which a plurality of self-advancing two-unit roof supports, carrying a conveyor means and elevated guide or support means for a mineral mining machine, are advanced collectively by successively advancing the units of the supports, the conveyor means being positioned so that as the supports are advanced mineral is collected and carried away by the conveyor means to, for example, a conveyor set at an angle (e.g. normal) to the mineral face.

The expression "two-unit roof supports" where used in this Specification is intended to include supports having units one behind the other and also supports having units in side-by-side relationship.

According to a further feature of the present invention there is provided a mine roof support comprising front and rear or side-by-side support units connected together by pressure-fluid actuated means operative to advance the units in turn, a forwardly projecting member on the front of the support being adapted, in conjunction with corresponding members of other supports positioned along a mineral face, to carry elevated guide or support means

2

for a mineral mining machine, the front of the support having or being adapted to have mounted on it a conveyor means for collecting and carrying away the mined mineral.

5 In one preferred arrangement a part of the conveyor means on the front of the front units of the supports is in the form of a ramp plate so that the mined mineral is gathered onto the conveyor means as the support system is advanced.

Where the face conveyor means comprises an endless conveyor the front support unit, or at least one leg or prop thereof, is positioned between the oppositely moving lengths or runs of said endless conveyor. Such an arrangement has the advantage that the front support units are set relatively close to the mineral face as compared with arrangements in which the whole of the conveyor and a loading ramp associated therewith are located to the front of the roof supports.

A convenient form of endless conveyor is that comprising a series of paddles attached to an endless chain and arranged to travel along troughs or the like.

As an alternative to an endless conveyor the conveying means may comprise a ramp at the front of the supports which, as the supports are advanced, picks up the mined mineral and directs it onto a longitudinal conveyor (e.g. a jogging conveyor) at the rear of the ramp.

The members on the supports which carry the guide or supporting means for the mineral mining machine may be adjustable in a vertical plane to enable the machine to be steered or adjusted in accordance with any faults or undulations in the mineral seam being mined. This adjustment may be effected by hydraulic ram means.

The conveyor will also have a degree of flexibility in the vertical plane but generally it will be a rigid unit so far as any lateral movement is concerned inasmuch as it is proposed to advance it bodily when a plurality of the front units of the supports are advanced.

The invention will be further described, by way of example, with reference to the accompanying drawings which show the invention more particularly as applied to the cutting or mining of the usual stable at the end of the coal face. The invention is, of course, also applicable to the longwall mining of the face.

In the drawings:

FIGURE 1 is a diagrammatic plan view with the equipment according to the invention installed therein,

FIGURE 2 is a diagrammatic side elevation of the equipment shown in FIGURE 1,

FIGURE 3 is a side elevation of one of the roof supports, and its associated equipment, several of which go to make up the roof supporting and mining system shown in FIGURES 1 and 2, and

FIGURE 4 is a plan view of FIGURE 3.

The roof support and mining system shown in FIGURES 1 and 2 comprises a plurality of roof supports spaced apart along the face F.

Each roof support comprises a rear unit and a front unit. The rear unit has a base 10 on which there is mounted, in pairs, one behind the other, hydraulically extensible telescopic legs or props 11. The props 11 support on their upper parts in the usual way a roof-engaging structure or canopy 12. The front unit of the support comprises a base 13 on which there is mounted a single hydraulically extensible telescopic leg or prop 14. The prop 14 supports at its upper part in the usual way a cantilever roof-bar 15.

Each roof support also includes a hydraulic support advancing ram having its cylinder 17 connected (e.g. by laterally projecting trunnions) to the rear unit of the support and its piston 18 connected to the front unit of the support.

The base of the front unit of the support also carries bearing brackets 19 which pivotally support, at 20, a forwardly projecting arm or cantilever 21. The arm 21 is supported by a hydraulic ram 22.

The arms 21 of the several roof supports serve to support between them the rails 23 on which the coal cutting or other mineral mining machine runs along the face. The rails 23 may be in sections coupled together as indicated at 24 in FIGURE 4. The coupling provides for flexibility in the vertical plane and rigidly against lateral flexing.

The front unit of each support also carries conveyor sections comprising a ramp plate 25 and a trough 26. An endless chain 27 carrying paddles or the like 28 runs along the ramp plate 25 and the trough 26. The ramp plates and troughs 25 and 26 of neighbouring roof supports are coupled together by coupling devices 29 which give the conveyor as a whole some vertical or up-and-down flexibility.

The system and equipment above described is operated as follows:

As the cutting machine travels along the rails 23 coal is cut and dislodged from the face and deposited on the ramp 25 and neighbouring parts of the conveyor. This coal is moved along the ramp 25 and subsequently along the trough 26 until it is deposited in a road-head conveyor 30 as shown in FIGURE 1.

When the cutting machine has removed a complete web of coal from the face it is necessary to advance the mining and roof support system. To do this the legs 14 of the front units of the several supports are lowered slightly to relieve them of roof pressure. The rams 17, 18 of the several supports are then advanced so that they push forward the front units of the supports together with the rails 23 and conveyor 25, 26, 27, 28 carried by said units. As the front units of the supports are advanced the ramp plates 25 gather up any coal which they have not received during the passage of the cutting machine and such coal is taken up by the paddles 28 and carried to the road-head conveyor 30.

It will be appreciated that the cutting machine can remain on the rails 23 during the advance thereof towards the face. The machine cuts (cuts) in during advance of the forward support unit.

The canopy 12 is slotted, as shown in FIGURE 3 to receive the cantilever roof-bar 15 so that said roof-bar can move forwardly relatively to the canopy 12 and provide roof support close up to the newly exposed face.

When the front units of the supports have been fully advanced their legs 14 are extended so as to secure them between floor and roof. The legs 11 of the rear support units are then lowered slightly so as to relieve them of roof pressure. The ram 17, 18 is then retracted so that the rear support units are brought forwardly to their normal position in relation to the front units as shown in FIGURE 2. The legs 11 are then extended so as to secure the rear units of the support firmly between floor and roof. The system is then ready for the coal cutting machine to cut a further web of coal from the face.

The coal cutting machine can be steered or adjusted vertically relatively to the face by adjusting the arms 21 by means of the hydraulic jacks 22.

Where the two units of each support are in side-by-side relationship one of each unit may have a cantilever, simi-

lar to the cantilever 21, on its forward part and carrying a section of rail adapted to form a part of a track for the coal cutting machine. Similarly, the front of one or each unit may carry a section of the conveyor 25, 26, 27, 28.

I claim:

1. A mineral mining arrangement including a plurality of self-advancing roof supports which are spaced apart along the length of a mineral face, an elevated forwardly projecting cantilever member pivoted at the front of each support, a pressure-fluid jack supporting each such cantilever member for vertical adjustment thereof, a section of track, for a mineral mining machine, on each of said elevated forwardly projecting cantilever members, a section of conveyor at the front of each support and positioned immediately below the elevated forwardly projecting cantilever member thereof, said sections of track and sections of conveyor on the plurality of supports aligning with one another when the supports have all been advanced towards said mineral face preparatory to the mining of mineral therefrom and the track sections so aligned serving as a track for guiding a mineral mining machine along said mineral face and the conveyor sections when so aligned receiving said mined mineral.

2. A mining arrangement as claimed in claim 1 wherein means is provided for hingedly connecting said track sections together end-to-end for vertical articulation but rigidly against lateral flexing.

3. A mining arrangement as claimed in claim 1 wherein means is provided for hingedly connecting said conveyor sections together for vertical articulation but rigidly against lateral flexing.

4. A mining arrangement as claimed in claim 1 wherein a forward part of each section of conveyor is in the form of a ramp plate which is operative to pick up mined mineral as the support is advanced.

5. A mining arrangement as claimed in claim 1 wherein in a chain means travels along said conveyor sections and said chain means carries scrapers which convey mined mineral along the conveyor sections.

6. A mining arrangement as claimed in claim 1 wherein in the conveyor sections form part of an endless conveyor between the runs of which hydraulically extensible props of the roof supports are positioned.

7. A mining arrangement as claimed in claim 1 wherein in the conveyor sections form an endless conveyor, lengths of which run in opposite direction along the mineral face, the length furthest from said face discharging mineral into a further conveyor disposed at an angle to it.
